SANITARY DRINKING PROTECTOR

Vincent Arato and Antonio Gallucci,
Peekskill, N. Y.

Application June 10, 1937, Serial No. 147,443

1 Claim. (Cl. 65—13)

This invention relates to lip protectors for beverage containers, as glass tumblers, goblets, cups, mugs and the like.

An object of the invention is to provide a sanitary shield, readily applied to any of the usual forms of drink containers, whereby the lips are prevented from coming in contact with the rim of the container, but which in nowise interferes with imbibing the liquid therein.

10 A further feature resides in the provision of a lip protector for glasses that prevents cutting the lips by contact with raw or broken edges on the rim.

Another purpose is to produce a device for fulfilling the foregoing objects, that is easily applied or removed, which adheres frictionally to the wall of the glass, and is so inexpensive to construct that it may be discarded after a single use by an individual without material loss.

20 These meritorious objects are accomplished by the novel construction and arrangement of simple parts, hereinafter described and illustrated in the accompanying drawing, forming a part of this disclosure, and in which:—

25 Figure 1 is a perspective view showing an embodiment of the invention and illustrating its application.

Fig. 2 is a similar view showing a modification in construction.

30 It is well known that the use of a common drinking glass promiscuously by the public is highly fraught with danger, by reason of the possibility of communicating disease, is unsanitary, uncleanly and distasteful in the extreme to 35 sensitive and discriminating individuals.

Not infrequently the edges of cups and glasses become chipped, cutting the lips and causing abrasions, which the use of the present device wholly avoids.

40 Referring now to the drawing in further detail, a conventional type of drinking glass, designated by the numeral 5, is shown in Figure 1, the same having a thin rim 6 at its upper edge.

The protecting guard 7 is shown as comprised 45 of a thin, generally rectangular strip of elastic, waterproof material such as indurated fibre, Celuloid, or similar thin fairly stiff substance capable of receiving and retaining the form given it.

This guard may present a crowned upper edge or flat, as preferred; in any case its main body portion is curved arcuately conformable to a glass but of slightly less radius to fit snugly around a portion of its circumference.

5 Extending integrally from its end edges are projections 8, curved re-entrantly, as at 9, infolded and creased, as at 10, and so shaped as to act efficiently as a clamp, straddlingly engaging the interior surface of the glass to be frictionally retained over its edge, but obviously removable at will.

In the modification, shown in Figure 2, the guard 15 may be made of less expensive material presenting the same general characteristics and 15 provided with plain extensions 16 at its end, which may be fancifully curved and adapted to embrace the exterior of the glass only.

Wing-like clamps 17 are firmly attached, by 20 tubular rivets 18, to these end extensions and are provided, at their upper portions, with folds 19 down-reaching to produce clamp elements 20 adapted to grip the inner surface of the glass, as clearly indicated.

The simplicity of the device, as well as its construction and use, is apparent, and it will be obvious that an adequate means of protection is provided for drinking glasses of any type and any shape in general.

Having thus described the invention and set forth the manner of its construction and application, what is claimed as new and sought to secure by Letters Patent, is:—

A lip protector for drinking glasses comprising 35 an arcuate strip of stiff, nonabsorptive material shaped to closely engage the exterior of a glass at its upper portion and to extend thereabove over a portion of its circumference, integral tab extensions at each end of said strip level with 40 the rim of the glass, resilient clamp members folded to extend over the rim of the glass and contact its interior adjacently thereto, and tubular rivets uniting said clamp members to said extending tabs.
